Inventor

Maurice Russell Berger

By William J. Gustafson

Attorney

UNITED STATES PATENT OFFICE.

MATTHEW RUSSELL BERGER, OF PHILADELPHIA, PENNSYLVANIA.

GUTTER-HANGER SHANK.

Application filed January 12, 1925. Serial No. 1,829.

To all whom it may concern:

Be it known that I, MATTHEW RUSSELL BERGER, a citizen of the United States, residing at Philadelphia, in the county of 5 Philadelphia and State of Pennsylvania, have invented a certain new and useful Gutter-Hanger Shank, of which the following is a specification.

This invention, generally stated, relates to 10 eave trough or gutter hangers, of the type in which the shank is formed of a plate and stem adapted to be secured to square box cornices and has more especial relation to the general style of shank patented to me 15 under date of September 19, 1922.

While my patented shank has proven commercially successful, practice dictates that when applying the same to a so-called square box cornice, which slightly inclines or slants, 20 it is sometimes necessary to bend the stem in order to properly position a circle and the gutter with respect to the eaves. Such practice has the tendency to weaken the connection between the stem top and plate. The 25 weakening of parts just referred to is accentuated to a degree because of careless handling upon the part of the workman erecting the gutters.

The leading object of the present invention 30 is to overcome the above described disadvantageous features and provide a shank for gutter circles comprised of a stem and plate in which the parts are so arranged with respect to one another that the stem, 35 which is rigidly joined to the plate, may be bent forwardly, rearwardly, to the right, and to the left with respect to the plate without weakening in the least degree said rigid connection, even though carelessly 40 handled by workmen. Other and further objects not at this time appearing will be referred to hereinafter.

The invention consists of the novel construction hereinafter described and finally 45 claimed.

The nature, characteristic features and scope of the invention will be more fully understood from the following description taken in connection with the accompanying 50 drawings forming part hereof, and in which:

Fig. 1, is a fragmentary view in elevation of a roof having an inclined or slanted square box cornice and illustrating the shank 55 of the invention as secured thereto.

Fig. 2, is a view in front elevation of the shank embodying the invention.

Fig. 3, is a rear view thereof.

Fig. 4, is a view thereof in side elevation.

Fig. 5, is a top or plan view thereof; and 60

Fig. 6, is a fragmentary view in front elevation illustrating an alternative style of plate.

For the purpose of illustrating my invention I have shown in the accompanying drawings two forms thereof which are at present preferred by me, since the same have been found in practice to give satisfactory and reliable results, although it is to be understood that the various instrumentalities 65 of which my invention consists can be variously arranged and organized and that my invention is not limited to the precise arrangement and organization of the instrumentalities as herein shown and described. 70

Referring now to the drawings in detail and more especially to Figs. 2 and 5 inclusive, the numeral 1 designates what is termed in the roofing supply trade a plate. In practice it is made in one piece of thin metal, 80 preferably wrought iron, and while the configuration thereof may vary, for illustrative purposes I have shown the same of rectangular configuration in said figures. The plate 1 has stamped therefrom a central, forwardly extended, vertical web or rib 2, having a relatively flat outer face. This web or rib 2 serves to form upon the plate rear a vertically extended recess or channel 3. The plate is provided with a plurality of apertures 4 for the accommodation of securing devices as nails, screws and the like. The stem, as it is called in the trade, is also made of wrought iron or of copper or brass in one piece and is of channel or U-shaped 85 cross-section. Its upper end 5 is fitted to the web or rib 2 by having the channel portion thereof engage over said rib or web throughout the major portion of the extent thereof, tongue and groove fashion. The 90 said end 5 of the stem is rigidly secured to the web or rib 2 to preclude movement in any direction of either of said members with respect to the other. This is preferably accomplished by means of a rivet 6, as shown in the drawings, in which case the butt end 7 of the rivet is contained wholly within the vertical recess at the rear of the plate, so as not to project beyond the flat 95 rear face of said plate. In lieu of a rivet 100

one or more bolts and nuts may be employed, the stem and plate may be welded one to the other, or in fact any satisfactory means of rigidly securing these parts together may be practiced as may be found most desirable. Immediately below the plate 1, the stem is twisted outwardly, as designated by the reference numeral 8, so that the lower portion 9 of the stem in manufacture is disposed substantially at right angles to the upper part of the stem and to said plate as clearly seen in Fig. 4. Thus it is seen that the inner edge 10 of the said part 9 of the stem is flush with the inner face of plate 1, and said inner edge aligns with the recessed portion of the plate rear, see Fig. 3. The portion of the stem below the twisted portion thereof is laterally apertured as at 11 for gutter circle attachment.

As previously stated the shank as manufactured is arranged at right angles to the upper part of the stem and plate. When applying a gutter hanger to a cornice having an incline or slant as designated by the numeral 12 in Fig. 1, the workman attached plate 1 and its stem to the cornice by means of nails or the like. Obviously the stem will then incline in parallelism with the cornice which is most undesirable.

The workman then with a suitable tool as a monkey-wrench twists the stem outwardly so as to parallel the building front 13 as clearly illustrated in Fig. 1. Obviously the stem may be readily bent inwardly or to the right or left if desired as is readily apparent. Because of the rigid connection of the upper stem part with respect to the plate 1, the workman only moves the lower stem part and in no way weakens the said connection of parts, the advantages of which are readily apparent.

In Fig. 6, I have illustrated an alternative style of plate designated by reference numeral 14. The connection of stem with respect thereto is exactly the same as that hereinbefore described.

It will now be apparent that I have devised a novel and useful construction which embodies the features of advantage enumerated as desirable in the statement of the invention and the above description and

while I have in the present instance shown and described the preferred embodiments thereof which have been found in practice to give satisfactory and reliable results, it is to be understood that the same are susceptible of modification in various particulars without departing from the spirit of the invention or sacrificing any of its advantages.

What I claim is:

1. A shank of the character stated comprising a plate having a central, vertically disposed rib upon its outer face, a stem of channel formation fitted over said rib, that portion of the stem immediately below said plate being twisted to extend said stem outwardly and to bring its channel portion substantially at right angles to that channel portion fitted over said rib, and means for rigidly securing said stem to said plate.

2. A shank of the character stated comprising a plate having a central, vertically disposed, hollow rib extended from the outer face of said plate, a stem of channel formation, the upper part of said stem having its channel portion fitted over said rib to preclude lateral movement of said upper stem part, that portion of the stem immediately below said plate being twisted to extend said stem outwardly and to bring its channel portion substantially at right angles to that channel portion fitted over said rib, and a rivet passing through said stem and rib, the butt of said rivet being accommodated within the hollow of said rib.

3. A shank of the character stated comprising a metal plate having a rib formed upon its outer face, a stem of channel form fitted over said rib, that portion of the stem immediately below said plate being bodily twisted to extend at angle to said plate, and means for rigidly securing said stem with respect to said rib whereby movement of the upper stem part is precluded in all directions and whereby the lower stem part is capable of being moved in all directions without weakening of the means of attachment.

In testimony whereof, I have hereunto signed my name.

MATTHEW RUSSELL BERGER.
